UNITED STATES PATENT OFFICE.

FURMAN D. SPEAR, OF NEW YORK, N. Y.

SIGNAL LANTERN.

Application filed April 24, 1925. Serial No. 25,518.

To all whom it may concern:

Be it known that I, FURMAN D. SPEAR, a citizen of the United States of America, residing at New York, county of New York, 5 State of New York, have invented a new and useful Signal Lantern, of which the following is a specification.

Signal lanterns and particularly hand lanterns are subjected to extreme variations 10 of amount and direction of air pressure due to the necessary signaling movements as well as to the wind.

Owing to the conditions of use and especially for railroad signaling purposes it 15 is desirable that the lantern be as light and compact as is consistent with strength and capacity. It is also desirable that the lantern operate satisfactorily notwithstanding changes and variations in the quality or 20 kind of oil available for use.

I accordingly have designed a lantern of small size, in fact of something like 20 per cent less bulk or volume and over 30 per cent lighter in weight than the usual railroad 25 signal lantern. The globe may be as much as 36 per cent shorter in height and 50 per cent less in weight. I have also provided improved ventilation means to meet the changed 30 conditions incident to so great a reduction in size and that will maintain a reliable flame produced either from signal oil or from light fuel oils such as kerosene as may be required by governing conditions of different users.

35 In the accompanying drawings I have shown the preferred form of my invention together with certain modifications.

Fig. 1 is a side view and partial vertical section of the preferred construction.

40 Fig. 2 is a perspective view of the globe dome and holder shown in partial section.

Fig. 3 is a side view and partial vertical section of a modified construction of top and globe dome holder.

45 Figs. 4 and 5 are fragmentary sectional views showing other modifications of the globe dome and holder.

Fig. 6 is a side view and partial section of a wind breaker or deflector.

50 The frame 6 may be of any suitable construction and provided with any suitable form of handle 7.

The base 8 of the lantern, mounted in the

frame 6, may be of any suitable construction to hold a suitable form of lamp pot 9. 55

The lantern top 10 may be secured to the frame 6 in any suitable manner. The globe 11 is provided with a holder and dome member 12 within the lantern top which is yieldingly held in place, for instance, by a 60 spring 13 which is secured to the member 12. The member 12 is detachably held in the lantern top by a hook 10' which engages the cross-bar 12' when the member 12 is inserted and rotated into place. 65

The lamp may be provided with any suitable form of burner 14, and positioned, for instance, by a shoulder 15 in the lower part of the base and by flange 16 in the upper part of the base. The base is, of course, 70 provided with suitable air inlets, such as 17 and 18, as is customary. I also prefer to provide a guard flange such as 19 which surrounds the openings 18 so as to prevent air from blowing too directly therein and also so as to keep the rain out and serve to direct air into the openings 18 when the lantern is moved downwardly. The flange 16 is also preferably provided with air inlets 75 20 so that the air can pass to the flame of the burner. 80

I also prefer to provide asbestos gasket rings 21 and 22 for the edges of the globe so as to afford a more or less yielding seat which will be substantially air tight notwithstanding the irregularities of the edges of the globe. This construction also assures a uniform seat notwithstanding the variations in the diameters of the globe. The main part of the globe is preferably spherical in shape and so located with respect to the burner that the flame comes approximately in the center. 85 90

The top member in its preferred form has, what may be termed, a dome 23 with an outwardly flaring reflector flange 24. The dome is provided with openings 25 from which normally the products of combustion pass out. 95

The globe dome and holder 12 preferably has a flange 26 which provides a seat for the gasket 22 at the upper edge of the globe, a vertically disposed wall 27, a horizontally disposed ring 28, and a vertically disposed tube 29, and serves as a flue for the products 100 of combustion from the lamp. The broad 105

flat gasket 22 affords a tight joint and yet it is so arranged that the top can be closed down without tilting the globe as is necessary in many lanterns. When the lantern is 5 swung, in giving varying signal and especially in upward movement, it becomes necessary to furnish an additional air supply to the flame from the direction of the top of the globe. To do this without otherwise interfering with the action of the lantern when at rest is a difficult problem. I have found that this can be readily accomplished according to my invention by providing a number of openings such as 30 through 10 which air from the lantern top can be admitted and regulated by a baffle member 31. In the form shown in Fig. 1 I provide a separate series of air inlets 32 in the lantern top and also an outwardly extending flange 15 33 at the upper end of the globe dome. Preferably the globe dome is formed in three parts, as shown in Figs. 1 and 2, and the baffle member 31 has a flange 34 which is detachably secured in some suitable manner 20 to the wall 27, as for instance, by means of a bayonet joint 35. This makes it possible to readily detach the shield or slip it up so as to facilitate cleaning the walls. The cylindrical portion 29 is preferably secured to 25 the flange 36 which extends upwardly from the ring 28 either permanently or by means of a bayonet joint 37. Air passage 38 is provided to the perforated ring 28 either through or inside of the baffle member 31 30 so that air which comes into the top dome from the openings 32 may pass through the opening 38 and thence through the openings 30 into the top of the globe and thence to the flame. The flaring "wind breaker" 39 is suspended from some part of the globe dome (for instance the ring 28) in position 40 to deflect part of the air which may be forced down through the tube 29 and prevent it from directly striking the flame. The 45 wind breaker is preferably of bell-shape and has a curved surface extending from the lower end of the tube 29 downwardly and outwardly toward the upper end of the globe 11. In this way it is possible to obtain the proper balance between the air supply and the combustion exits so as to insure a steady flame which requires just enough air to support combustion without an excess of air which would extinguish the flame. 50 The member 39 also serves to deflect and assist in uniformly distributing air which is admitted through the inlets 30 in the member 12.

In the form shown in Fig. 3 the openings 60 40 in the lantern top are made sufficiently large to serve not only as exits for the products of combustion but for inlets for air in certain circumstances. In this case the air inlets 41 are in the tubular member 65 42 which carries the baffling member 43, having a

and the air from inside the lantern dome is admitted through the opening 44 beneath the baffle member to the openings 41.

In the form of globe dome and holder shown in Fig. 4 the air inlets 45 are in a vertical wall surrounded by a baffling member 46 while the air inlet 47 is formed between the upper inner edge of the baffling member and the tubular member 48.

In the form shown in Fig. 5 the air inlets 50 are formed in the horizontal ring of the globe dome and the baffling regulator 51 is secured to the tubular member 52 leaving an air inlet 53 at its lower edge.

In all of these constructions it will be noted that what may be termed the emergency air supply is furnished through the top of the lantern above the reflector 24 and that its passage into the globe dome is regulated by a baffling member which controls the volume of air to pass to the flame under certain conditions.

Notwithstanding the small size of this new lantern it has been found to work with entire satisfaction with various fuel oils and even under the most severe conditions of test.

I claim:

1. A signal lantern comprising a frame, a base secured thereto and having air inlets and a globe seat, a top member secured to said frame and having a dome with openings and a flaring reflector, a globe dome and holder mounted in said top and having a globe seat within said reflector and having a 100 air inlets communicating with some of the openings in the top dome above said reflector and a baffling member between said domes for regulating the volume of air to be admitted into said globe dome the lower part of said globe dome being imperforate and substantially preventing the passage of air into said top member from below said reflector.

2. A signal lantern comprising a frame, a base secured thereto and having lateral air inlets, a downwardly extending guard flange surrounding said inlets, said base having a globe seat, a top member having a laterally perforated dome and a flaring reflector, a globe dome movable in said top dome and having a globe seat and having air inlets communicating with some of the perforations in said top dome and a regulating baffle attached to said globe dome for controlling the volume of air passing from the top dome into the globe dome the lower part of said globe dome being imperforate and substantially preventing the passage of air into said top member from below said reflector.

3. In a signal lantern, a top member having a flaring reflector and with lateral openings above the reflector, a globe holder 120 having a dome mounted within said top

- member having a horizontal flange with air inlets communicating with some of the openings in said top member and a baffling member attached to the outer surface of said globe holder for regulating the air to be admitted from said top member to said globe holder.
4. In a signal lantern, a top member having a reflector with upper and lower sets of openings above the reflector, a globe holder having a dome mounted within said top member with air inlets communicating with the lower openings in said top member and a flange between the upper and lower sets of openings and a baffling member attached to the outer surface of said globe holder for regulating the air to be admitted to said globe holder.
5. A signal lantern comprising a base having air inlets and a globe seat, a top member having a dome with openings and a flaring reflector, a globe dome and holder mounted in said top and having a main central portion and having a globe seat within said reflector and having air inlets communicating with some of the openings in the top dome, above said reflector, a globe held in said seats, a wind breaker extending from the central portion of said globe dome downwardly and outwardly toward the upper end of said globe and a baffling member between said domes for regulating the volume of air to be admitted into said globe dome.
6. In a signal lantern, a top member having a flaring reflector with openings above the reflector, a globe holder having a dome mounted within said top member with air inlets communicating with some of the openings in said top member, a bell shaped wind breaker extending downwardly and outwardly from said dome below said air inlets and a baffling member attached to said globe holder for regulating the air to be admitted from said top member to said globe holder, said globe holder, wind breaker, and baffling member being all arranged above the lower edge of said reflector.
7. A signal lantern comprising a frame, a base secured thereto and having air inlets, a downwardly flaring guard flange surrounding said air inlets, a top member having a dome with two rows of perforations and a flaring reflector at its lower end, a globe dome movable in said top dome and having a main passage and having air inlets communicating with the lower perforations in said top dome, a globe held by said globe dome, a wind breaker at the upper end thereof below said main passage and having one end of smaller diameter than said main passage and a regulating baffle attached to said globe dome for controlling the air passing from the top dome into the globe dome.
8. In a signal lantern, a top member having a reflector with air openings above the reflector, a globe holder having a dome mounted within said top member with air inlets communicating with some of the openings in said top member, a bell-shaped wind breaker extending downwardly and outwardly from the central part of the dome and spaced apart from said dome so as to leave a passage through the center and around the sides to the center, and a baffling regulator attached to said globe holder for regulating the air to be admitted from said top member to said globe holder.
9. A signal lantern comprising a frame, a base secured thereto and having air inlets and a globe seat, a top member secured to said frame and having a dome with side openings and a flaring reflector at its lower end, a globe dome and holder mounted in said top and having a globe seat and having air inlets communicating with some of the side openings in the top dome above said reflector, a spherically shaped globe in said seats, a regulating baffling member opposite said air inlets for controlling the movement of air into said globe dome, and a wind breaker extending downwardly and outwardly from the central portion of said globe dome to the plane of the upper end of said globe with air passages from the center of the globe dome outside and inside of said wind breaker.
10. In a signal lantern, a top member having a reflector with upper and lower sets of openings above the reflector, a globe holder having a dome mounted within said top member with air inlets communicating with the lower openings in said top member, a tubular portion and a flange extending therefrom between the upper and lower sets of openings, an annular wind breaker extending from the lower end of said tubular portion to the lower end of said globe holder and having passages around and through it leading to the tubular portion, and a baffling member attached to the outer surface of said globe holder for regulating the air to be admitted to said globe holder.
11. A signal lantern comprising a base having air inlets, and having a globe seat, a top member having a dome with perforations and a reflector at its lower end, a globe dome movable in said top dome and having a tubular portion and a globe seat and having air inlets communicating with some of the perforations in said top dome above said reflector, a globe in said seats, a regulating baffle for controlling the volume of air passing from the top dome into the globe dome and a bell-shaped wind breaker extending from the lower part of said tubular portion to the plane of the upper end of said globe, and having an air passage leading downwardly through said tubular portion and outside of said wind breaker.

12. In a signal lantern, a top member having a reflector with upper and lower sets of openings above the reflector, a globe holder having a dome mounted within said top member with air inlets communicating with the lower openings in said top member, a tubular portion and a flange extending therefrom between the upper and lower sets of openings and an annular wind breaker extending from the lower end of said tubular portion to the lower end of said globe holder and having its inner diameter less than the diameter of said tubular portion and having its outer diameter larger than said tubular portion.
13. A signal lantern comprising a base having air inlets and a globe seat, a top member having a laterally perforated dome and a flaring reflector, a globe dome movable in said top dome and having a central passage 20 and having a globe seat and having air inlets communicating with some of the perforations in said top dome, a globe mounted in said seat and an outwardly and downwardly flaring wind breaker extending from the central portion of said globe dome to the upper end of said globe, and leaving passages through the center and around the outer edge of said wind breaker leading to said central passage.

FURMAN D. SPEAR.
